UNITED STATES PATENT OFFICE.

CHARLES E. CANNADAY, OF WASHINGTON, DISTRICT OF COLUMBIA.

INSIDE DOOR PROTECTOR AND GANGBOARD.

Application filed January 11, 1924. Serial No. 685,658.

To all whom it may concern:

Be it known that I, CHARLES E. CANNADAY, a citizen of the United States, residing at Washington, in the District of Columbia, 5 have invented certain new and useful Improvements in Inside Door Protectors and Gangboards, of which the following is a specification.

This invention relates to car door protectors and gang boards and has for an object to provide a protector for the inside of doors of freight cars and the like and as an improvement upon application Serial No. 662,874 filed September 15, 1923.

15 A further object of the invention is to provide a bail, properly hinged in the doorway of a car, with a gang board secured thereto in such manner as to move with the bail in its pivotal action and to move independently thereof under varying conditions.

20 A further object of the invention is to provide a bail pivotally mounted in a car door in such manner as to stand substantially vertically within the limits of the car door and to swing outwardly to substantially horizontal position in which position it is supported below the level of the car floor and to carry on said bail a gang board.

25 A further object of the invention is to provide improved means for pivoting the bail relative to the car whereby it is limited in its oscillatory movement between substantially a vertical position within the lines of the car door and substantially a horizontal position below the level of the car floor extending outwardly, and an improved type of gang board carried by the bail.

30 With these and other objects in view, the invention comprises certain novel parts, elements, units, combinations, constructions, mechanical movements, interactions and functions as disclosed in the drawings together with mechanical and functional equivalents thereof as will be hereinafter more fully described and claimed.

In the drawings:

35 Figure 1 is a view of the improved device as seen mounted in the car door observed from the outside of the car, the gang board being seen in elevation raised to a position inside the car door and to protect the car door from the lading.

Figure 2 is a vertical sectional view taken on line 2—2 of Figure 1. 55

Figure 3 is a horizontal sectional view taken on line 3—3 of Figures 1 and 2.

Figure 4 is a horizontal sectional view through portions of the car body showing the gang board in plan and in position to 60 operate as such gang board.

Figure 5 is a horizontal sectional view taken on line 5—5 of Figure 4.

Figure 6 is a view taken on the same plane as Figure 5 but showing the position of the gang board dropped down when it is removed from the supporting structure and out of danger position. 65

Figure 7 is an enlarged perspective view of the block employed for pivoting the bail. 70

Like characters of reference indicate corresponding parts throughout the several views.

The improved door protector and gang board which forms the subject matter of 75 this application is adapted to be associated with railway cars of the type ordinarily known as freight cars and represented broadly in the drawings by the parts indicated as A. The car is assumed to be 80 equipped with a door of the usual and ordinary type represented in the drawings as the sliding door B. Within the door way and adjacent to the side posts of such door way blocks C are employed, preferably by 85 being set into and approximately flush with the floor D of the car.

These blocks C are the means by which the device is secured to the car. The device comprises a bail 10 having a substantially 90 horizontal section with arms 11 turned substantially at right angles to the middle portion and provided with trunnions 12 at the ends.

These trunnions 12 are adapted to slide 95 into the block C in undercuts 13 of the grooves 14 and move backwardly in said groove until the bail is raised to substantially a vertical position against the shoulder 15, limiting said groove. To maintain 100 the bail in such pivoted position, a bolt 16, at each end, is inserted into and through the hole 17 of the block C and through underlying parts of the car structure whereby the trunnion 12 is maintained in pivoting position and the block C also main- 105

tained in rigid association with the car structure. Preferably also an auxiliary bolt 18 will be employed inserted through the hole 19 in the block, although such bolt 5 performs no function other than augmenting the rigidity of mounting of the block C.

Upon this bail 10 the gang board is mounted. The gang board preferably comprises a sheet 20 of rigid material, such, for instance, 10 as a plate of steel with cleats 21 secured rigidly to the under side of the plate and preferably in the form of angle iron, one web of each of which has a slot 22 through which the bail 10 is inserted. These slots 22 permit a considerable amount of adjustment of 15 the plate upon the bail, such, for instance, as indicated at Figures 4 and 5 whereby the plate, when operating as a gang board, may be moved within the limits of the car structure or moved outwardly a considerable distance to be supported wholly upon the bail, depending upon the interval of the car carrying the gang board and the structure supporting the outer end. Each cleat 21 is 20 accommodated in a slot 23 formed in the respective block C so that the plate 20 may rest substantially upon the block C and the floor of the car. As shown in the drawings, each block C may be lowered slightly below the 25 actual floor level, as for instance the thickness of the flange of the cleat 21, so that, when the flange of the cleat 21 rests upon the block C, the plate 20 may actually be exactly level with the floor or bear upon the 30 floor according to its position.

Preferably, the outer corners of the plate 20 are cut out at 24, the purpose for which, however, is not novel in the present application and is fully disclosed in said co-pending application Serial No. 662,874.

To maintain the plate 20 in substantially vertical position within the lines of the door B, to serve as a protector holding the lading away from contact with said door, means is 45 provided for engaging the upper edge of said plate comprising channel bars 25 pivoted to the door frame at 26 and adapted to embrace the upper edge of said plate 20. Preferably, these two bars 25 interlock by 50 forming a tongue 27 upon one which enters a groove 28 upon the other as indicated more particularly at Figure 1, although it is to be understood that the invention is not specifically limited to this form of locking means.

It will be noted especially from Figure 6 that, when the outer end of the plate 20 is without support, the relation of the slot 22 and bail 10 is such that the plate 20 may drop down to a substantially vertical position outside of the car. This mechanical movement is provided for the reason that it often occurs that the car carrying such gang board is moved during its use or before it has been returned to protecting position, or 60 65 the structure supporting the outer end of

the gang board, as for instance another car, has been moved from such supporting position. If remaining in outstanding relation to the car, it causes damage and injury to property and people but, if permitted to drop down to vertical position as shown at Figure 6, this danger is eliminated or at least minimized.

In use during transportation, the gang board will occupy the position shown at Figures 1 and 2 held in approximately vertical position at or slightly within the lines of the frame of the car whereby the lading engages against its plate and is restrained from damaging contact with the door itself, 75 preventing expensive and troublesome bulging of the door and loss of lading. When the car carrying this device reaches the position where the lading is to be transferred, the gang board is let down by raising the channel members 25 to release the upper edge of the gang board, it being then moved to substantially horizontal position as shown at Figures 4 and 5, the outer end being supported by a spotted car, a platform, a truck 80 or the like. As shown at Figure 5, the gang board may be moved a considerable distance laterally to accommodate for difference in spacing of the two supporting structures.

If now the car carrying the device or the 85 device supporting the outer end is moved, the gang board drops down at once to the position shown at Figure 6.

The gang board may also occupy this position in case the car carrying the same is co-acting with the car carrying a similar device, the device of the other car being employed for bridging the space between the two cars, one of said gang boards remaining inoperative as shown.

The car being again laden, the gang board is raised to vertical position by swinging first upon the bail, then swinging the bail therewith to substantially vertical position as shown at Figures 1 and 2 and locked by 100 the swinging down over the upper edge of the channel iron latches 25.

What I claim to be new is:

1. A protector for car doors comprising a bail pivoted within the lines of the car door, 115 and a plate carried by the bail adapted to swing with the bail to form a gang board and to swing independently of the bail to safe position.

2. A car door protector comprising a bail 120 having its lower ends pivoted below the lines of the car floor and bowed upwardly, a plate connected with the bail adapted to swing relative thereto and slide laterally and adapted to swing outwardly with the 125 bail and downwardly relative to the bail.

3. A car door protector comprising a bail having downwardly turned arms, means pivoting the downwardly extending extremities of the arms below the level of the car 130

floor, said pivoting means including also means for limiting the movement of the bail at substantially vertical and horizontal positions, and a plate pivotally and slidably mounted upon said bail.

4. A car door protector comprising a bail embodying a normally substantially horizontal middle section and right angularly turned arms at the ends, trunnions carried at the extremities of the arms, blocks rigidly secured to the floor of the car and providing means for pivotal connection with said trunnions, stops for limiting the movement of the bail substantially at vertical and horizontal positions, and a plate pivotally and slidably carried by the bail.

5. A protector for car doors comprising a bail embodying a substantially horizontal middle part and right angularly turned arms, pivotal connecting members carried at the ends of said arms, means co-acting with said pivotal members for attaching said bail to a car to provide for oscillation between substantially a vertical position and substantially a horizontal position, so positioned that in a vertical position the bail is within the limits of the car door and in horizontal position the central part is without the limits of the door, and a plate carried by the bail.

6. A car door protector comprising a bail mounted to oscillate relative to the car to occupy a vertical position within the limits of the door and a horizontal position without the limits of the door, a plate, and cleats secured to the under side of said plate provided with slots embracing said bail providing pivotal and sliding action of the plate relative to the bail.

7. In a car door protector, a bail having right angularly turned arms, a pivoting block at each end of the bail having slots formed for accommodating said arms, and common means for securing said block in rigid position in a car and maintaining the bail in pivotal relation to the block.

8. In a car door protector, a bail having right angularly turned arms with aligned trunnions at the extremities of the arms, a block for each arm, each of said blocks providing a slot proportioned to accommodate the arm and an undercut to permit the insertion of the trunnion into the block, and a bolt inserted through the block maintaining said block in rigid engagement with the car and the trunnion in pivotal engagement with the block.

In testimony whereof, I affix my signature.

CHARLES E. CANNADAY.
